Fig 2.

UNITED STATES PATENT OFFICE.

CHARLES D. EDWARDS, OF ALBERT LEA, MINNESOTA.

ROAD GRADER.

Application filed April 22, 1921. Serial No. 463,533.

To all whom it may concern:

Be it known that I, CHARLES D. EDWARDS, am a citizen of the United States, residing at Albert Lea, in the county of Freeborn 5 and State of Minnesota, have invented certain new and useful Improvements in Road Graders; and I do hereby declare the following to be a full, clear, and exact description of the invention, such as will enable others 10 skilled in the art to which it appertains to make and use the same.

My invention relates to road graders and particularly to that type of a road grader wherein the scraper blades are supported 15 from a "reversing circle" mounted on a supplemental frame and capable of lateral, vertical and angular adjustments. My invention is directed chiefly to improved means for imparting vertical and angular adjustments 20 to the supplemental frame that carries the scraper blade.

In the accompanying drawings, which illustrate the invention, like characters indicate like parts throughout the several 25 views.

Referring to the drawings:

Fig. 1 is a side elevation showing the improved road grader;

Fig. 2 is a transverse vertical section taken 30 approximately on the irregular line 2—2 of Fig. 1;

Fig. 3 is a fragmentary view on the same line as Fig. 2, but showing different adjustments of the scraper blade; and

Fig. 4 is a fragmentary elevation showing 35 a modified form of link connection between the lifting arm and draw bar frame.

The road grader comprises the usual rear wheels 4 journaled on the rear axle 5 and 40 front wheels 6 journaled on the front axle 7, which latter, by the customary bolster 8, is connected to the pole 9.

As a feature of this invention, the main frame of the machine is made up chiefly of 45 a pair of laterally spaced frame bars 10, preferably angle irons, arranged to form a sort of inverted V-shaped arch with its high point at its intermediate portion. The rear ends of these frame bars 10 are secured to 50 the rear axle 5 by the usual or any suitable means, and the front ends of said bars are connected to the bolster 8 by the customary pivot, not shown.

The scraper blade 11, which is of the usual or any suitable form, is attached to 55 the lower ends of downwardly curved bars 12, the upper ends of which are rigidly secured to the "reversing circle" 13, and this reversing circle is mounted for horizontal rotary or oscillatory movements in the usual 60 way on a supplemental frame made up of forwardly extended draw bars 14, the rear ends of which are bolted or otherwise rigidly secured to a cross bar 15. At their front ends, the draw bars 14 are connected to the 65 bolster 8, with freedom for substantially universal movements, to wit: vertical, lateral and angular movements, by the usual or any suitable means, not shown.

The numeral 16 indicates a transverse anchor bar rigidly connected to the rear portions of the frame bars 10 by brackets 17. The numeral 18 indicates a transversely oblique thrust link that flexibly connects the cross bar 15 of the supplemental frame 75 to the anchor bar 16 to hold the scraper blade to its work and against lateral shifting movements when once set to work in a particular position. The function and arrangement of this thrust link, as well as the 80 particular connections between the supplemental frame and the main frame or front bolster, constitute, per se, no part of the present invention, may be of any of the different well known constructions and, 85 hence, need not here be further considered.

Rigidly secured to the main frame bars 10, at the upper angles thereof, by means of bolts 19 or the like, are plates or brackets 20, which serve the combined purpose of 90 bearings and gusset plates. In their first noted function, they reinforce and brace the bars 10 at their upper angles and, in their second function, they serve to support devices for raising and lowering and angularly adjusting the scraper blade in respect 95 to the road bed, so as to set the lower edge of the scraper at any desired altitude for scraping the road bed horizontally or for crowning the same.

Journalized on the plates 20 and in brackets 21 secured to the bars 10 are short shafts 22 provided with hand wheels 23 at their inner ends and, between said plates and brackets, with worms 24. The worms 24 independently engage segmental worm gears 100 105

25 journaled on pins 26 secured to said plates 20. These segmental gears 25 are provided with outwardly extended arms 27 that are connected by links 28 to the opposite sides of the supplemental scraper-supporting frame. In the preferred arrangement, the links 28 have perforated upper ends 29, which, by bolts 30, are adjustably pivoted to the arms 27; and the lower ends 10 of said links have laterally bent ends 31 adapted to be inserted, at will, either through perforations 32 in the ends of the cross bar 15 or, in perforations formed in the lower portions of depending lugs or 15 end portions 33 that are rigidly secured to the ends of said cross bar. The adjustable connections between said links and arms 27 and cross bar 15 gives a large range of adjustability for setting the scraper blade 20 either in the one direction or the other at very considerable angles to the horizontal.

By independent manipulation of the hand wheels 23, the angle of the scraper blade in respect to a horizontal may be quickly adjusted and the scraper blade may be quickly raised or lowered. Obviously, the two hand wheels can be operated simultaneously or at different times. Both are within easy reach of the operator on the seat 34.

30 In the above arrangement, the main frame, made up of the bars 10, is thrown high up at its intermediate portion so as to give good clearance for the supplemental frame and reversing circle, and also, this 35 form gives said main frame increased load-carrying strength. By mounting the worm and worm gear below or in the raised angles of the main frame bars, they are hung out of the way or, in other words, are brought low 40 down, as required, without projecting them or their supports above the main frame bars. Moreover, with the bearing plates or brackets rigidly secured to the crowns of the arch bars, depending therefrom and reinforcing 45 said angles, said plates are caused to act not only as suspended bearings but as trussing brackets. Thus, they not only strengthen and truss the arches of the bars, but are themselves supported in such a way that 50 they are rigid against lateral bending strains such as produced by the load transmitted thereto through the worms, worm gears and lifting arms. Thus, from all points of view, it is highly important that these bearing 55 plates or brackets be extended below the tops or arches of the side bars and that the worm gears and arms be mounted therein or thereon within the angles and below the crowns of said frame bars.

60 In Fig. 4, I have illustrated a slight modification in which the links 28^a, at their upper ends, are simply bent laterally and inserted through the ends of the arms 7 and, at their lower ends, are bent laterally and adapted 65 to be inserted, at will, either through the

perforations in the ends of the bar 15 or through the perforations in the depending lugs 33. Thus, the supplemental frame, including the cross bar 15, may be vertically adjusted on the links 28^a without requiring 70 vertical adjustments of said links in respect to the arms 27.

What I claim is:

1. In a road grader, the combination with a frame having arched side bars and bearing 75 brackets secured to the crowns thereof and depending therefrom, of a scraper and draw bar connections between the same and the main frame structure, and means for vertically adjusting the opposite ends of said 80 scraper blade, comprising crank arms and operating devices mounted on said bearing brackets below the crowns of said frame bars.

2. In a road grader, the combination with 85 a frame having arched side bars and bearing brackets secured to the crowns thereof and depending therefrom, of a scraper and draw bar connections between the same and the main frame structure, and means for vertically adjusting the opposite ends of said 90 scraper blade, comprising crank arms and operating devices mounted on said bearing brackets below the crowns of said frame bars, said brackets being in the form of gusset plates that truss and reinforce the upper 95 angles of said frame bars.

3. In a road grader, the combination with a frame having arched side bars and bearing brackets in the form of gusset plates rigidly 100 secured to the crowns or upper angles of said side bars and reinforcing the same and depending therefrom, of a scraper and draw bar connections between the same and the main frame structure, means for independently vertically adjusting the opposite 105 ends of said scraper blade comprising co-operating worms and worm gears mounted on said gusset plates below said frame bars, said gears having projecting arms, links 110 connecting said arms to said draw bar connection, and hand-operating devices for independently rotating said arms.

4. In a road grader, the combination with a frame having arched side bars and bearing 115 brackets in the form of gusset plates rigidly secured to the crowns or upper angles of said side bars and reinforcing the same and depending therefrom, of a scraper and draw bar connections between the same and the 120 main frame structure, means for independently vertically adjusting the opposite ends of said scraper blade comprising co-operating worms and worm gears mounted on said gusset plates below said frame bars, said 125 gears having projecting arms, links connecting said arms to said draw bar connection, and hand-operating devices for independently rotating said arms, said links, at their lower ends, having laterally bent ends 130

and said draw bar connection having vertically spaced holes to receive said laterally bent ends.

5. In a road grader, the combination with a truck, the main frame of which has angular arched laterally spaced main bars, of a draw bar frame flexibly connected to the front portion of said truck, a reversing circle applied to said draw bar frame, a scraper 10 blade connected to and adjustable with said reversing circle, bearing plates rigidly secured to the crowns or angular upper portions of said main frame bars and depending therefrom and reinforcing the same, co-operating worms and worm gears mounted on 15 said bearing plates below the top thereof, said worm gears and said worms having in-

dependent hand wheels, and links independently connecting said arms to the opposite rear portions of said draw bar frame. 20

6. In a road grader, the combination with a frame having upwardly arched side bars and bearing brackets secured to the crowns thereof and extended within the angle below said crowns, of a scraper and draw-bar connections between the same and the main frame structure, and means for adjusting said scraper vertically comprising worm and worm gear connections mounted in said bearings and working below the crowns of 30 said arched frame bars.

In testimony whereof I affix my signature.

CHARLES D. EDWARDS.
